UNITED STATES PATENT OFFICE.

FRANK K. WARD, OF WASHINGTON, DISTRICT OF COLUMBIA.

DESIGN FOR A CREAM-SKIMMER.

SPECIFICATION forming part of Design No. 21,418, dated March 22, 1892.

Application filed February 15, 1892. Serial No. 421,637. Term of patent 14 years.

To all whom it may concern:

Be it known that I, FRANK K. WARD, a citizen of the United States, residing at Washington, in the District of Columbia, have invented and produced a new and original Design for a Cream-Skimmer, of which the following is a specification.

This design has for its object to provide a novel cream-skimmer, which is ornamental and presents a very attractive, handsome, and peculiar appearance to the eye.

The leading feature of the design consists in a cream-skimmer having its body in the form of a hollow cone, provided with a handle extending from the interior central part of the hollow cone.

The design is illustrated by the accompanying drawings, in which—

In the accompanying drawings the numeral 1 indicates the skimmer-body, which is in the form of a hollow cone, and 2 indicates a handle extending from the cone. In the example illustrated the handle extends from the interior central part of the hollow cone. The base of the cone is provided with an annular feather or knife edge 3. The handle, as shown, comprises a rectilinear rod having longitudinal fluted portions 4 and an enlarged grip or finger piece 5 of a suitable ornamental appearance.

The design provides an ornamental and handsome cream-skimmer, which presents a peculiar appearance to the eye.

What I claim is—

The design for a cream-skimmer having its body in the form of a hollow cone, provided with a handle extending from its interior central part, substantially as shown and described.

In testimony whereof I have hereunto set my hand and affixed my seal in presence of two subscribing witnesses.
